INC., OF NEW YORK, N. Y., A CORPORATION OF NEW YORK

WEB ROLL LOADING MECHANISM FOR PRINTING PRESSES

Application filed June 26, 1928. Serial No. 288,389.

The present invention relates to means for supporting web rolls used in connection with rotary printing presses which print on a web of paper.

5 When the web is being fed to the press, the web rolls are held so they may be rotated to unwind them, and they are sometimes mounted on a shaft or spindle which passes through the core of the roll and extends beyond both ends. In these cases the 10 spindle is usually centralized and secured to the roll by tapered bushings which engage the ends of the roll core, and the projecting ends of the spindle rest in suitable bearings 15 so the roll may be rotated.

The use of spindles is objectionable on account of their weight, for they cannot be conveniently handled otherwise than manually, and a further objection is that when 20 using them, considerable working space beyond the end of the roll is required in which to align the spindle with the roll before it can be inserted.

25 Supports that directly engage the roll core and do not require the use of spindles are sometimes used, and a support of this type is shown herein. One objection to this type of support as heretofore used, is the difficulty that is experienced in loading the rolls 30 into the support, which necessitates having the support arranged so that it can be lowered to bring it into alignment with the core of the roll. This is necessary in order that the cones which form the pivots for rotating the 35 roll can be inserted and the support then raised, allowing the roll to turn for unwinding.

An object of the invention herein disclosed 40 is to provide a convenient member for the attachment of hoisting gear to web rolls for lifting them to the position where they can be engaged by supports on which they may be rotated for unwinding.

45 Another object of the invention is to provide a device for the purpose stated that can be used in a small working space.

50 Still another object of the invention is to provide a device for use with web roll supports that is of generally improved construction, simple, durable, inexpensive in con-

struction, and practical, serviceable and efficient in its use.

With the foregoing and other objects in view which will appear as the description proceeds, the invention resides in the combination and arrangement of parts, and in the details of construction hereinafter described and claimed, it being understood that various changes in the precise embodiment of the invention herein disclosed may be made within the scope of which is claimed, without departing from the spirit of the invention. 55

The invention has been illustrated in its preferred form in the accompanying drawings, wherein; 60

65 Figure 1 is a side view partly broken away and partly in section, of a web roll supported for unwinding, showing the hoisting gear attached.

70 Figure 2 is a fragmentary view partly in section showing the unwinding support disengaged from the roll; and

75 Figure 3 is a fragmentary view partly in section showing a modified form of the invention.

78 Referring to the drawings, 11 indicates a web roll having a tubular core 12. Arms 13 and 14 extend from a structure not shown which may be the frame of the press or they may be arms of a multi-armed rack adapted 80 to hold a plurality of web rolls. The arms 13, 14 are provided with cylindrical bores 15 in each of which a support 16 is fitted to slide freely. The support 16 has a rack 17 cut in its side which meshes with the pinion 18 secured to the shaft 19. The lever 20 has a hub 21 that is also secured to the shaft 19. It will thus be understood that the lever 20 provides a convenient means for rotating the shaft 19 and thus causing the sliding support 85 16, to move to the right or left as desired.

One end of the support 16 is made with a reduced diameter 22 and forms a seat for the roller bearing #23 on which the sleeve 24 turns. A thrust washer 25 is set in a recess 90 in the support 16 and provides an abutment for the ball thrust bearing 26 which bears against the flange 27 on the sleeve 24.

95 A thimble 28 is fitted over the sleeve 24 and rotates with it, being held in position by the 100

washer 29 which is in turn held by the screw 40, threaded into the reduced portion 22 of the support, this assemblage forming a bearing on which the web roll may be rotated.

5. A lifting member 31 is made with a cylindrical portion 32 that fits within the core 12 and a head portion extending beyond the core and having an opening 33 shaped to fit the thimble 28 of the support. In the preferred 10 construction, it also has a groove 34 which forms a seat between the flanges 35 and 36 and serves to position the engaging member or hook 37 of a hoisting gear when it is brought into engagement with the lifting member.

15. Referring to Figure 3 which shows a modified form of the invention, the plug 38 is made with a recess 39 into which the race 40 of a ball bearing is fitted. The cone 41 of the bearing can revolve on the balls 42 but 20 is held in place by the collar 43 which is secured to the plug by screws 44.

The head portion of the lifting member in this form is made solid and has a boss on its outer end and concentric therewith, arranged 25 to engage the cone 41. It will be understood that with the parts in the position shown in Figure 3, the roll may be rotated on its axis for unwinding and that engagement with and disengagement from the support may be 30 conveniently accomplished.

In practice, with the web roll resting on the floor, or it may be on a truck on which it is brought to the press, the lifting members 31 are inserted in the ends of the roll and the 35 hooks 35 of a hoisting gear placed in the grooves 34 of the lifting members. The roll is then lifted to align its axis with the thimbles 28 of the support bearings which are then moved into the openings 33 of the 40 hoisting sleeve. The hoisting hooks are then disconnected leaving the roll free to turn for unwinding.

While a groove has been selected as the 45 preferred means of holding the hoisting connections in position it will be understood that various modifications of this arrangement may be made within the scope of the claims.

What I claim is:

1. In a web supply mechanism for a printing press, a web roll having a tubular core, 50 separate lifting members fitting within each end of the core, a hoisting mechanism, and supports having bearings adapted to engage the lifting members whereby the roll may be 55 rotated about its axis; said lifting members each having a head portion formed to engage the end of the core and a circumferential groove to engage with a hook of a hoisting gear.

60. 2. In a lifting member for a web roll having a tubular core, a substantially cylindrical portion adapted to fit in the core, a head portion of larger diameter adapted to engage the 65 end of the core, and a recess in the head portion concentric with the axis of the cylindrical

portion and fitted to a bearing on which the lifting member may be rotated; said head portion being formed with a seat for an engaging member of a hoisting gear.

3. In a lifting member for a web roll having a tubular core, a substantially cylindrical portion adapted to fit in the core, a head portion of larger diameter adapted to engage the end of the core, and a recess in the head portion concentric with the axis of the cylindrical portion and fitted to a bearing on which the lifting member may be rotated; 70 said head portion having a circumferential groove forming a seat for a hoisting hook.

75. In testimony whereof, I affix my signature. 80

FREDERICK LAMATSCH.
